(57) CLAIM

The ornamental design for a portable speaker, as shown and described.

DESCRIPTION

FIG. 1 is a front perspective view of the portable speaker of the present invention showing my new design;
FIG. 2 is a front side elevational view thereof;
FIG. 3 is a back side elevational view thereof;
FIG. 4 is a side elevational view thereof;
FIG. 5 is another side elevational view thereof;
FIG. 6 is a top plan view thereof; and,
The broken lines in the drawings illustrate features of the portable speaker that form no part of the claim.
